(57) **CLAIM**

The ornamental design for a stereo monitor receiver, as shown and described.

DESCRIPTION

FIG. 1 is an isometric view of a stero monitor receiver showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof; and,

FIG. 7 is a bottom plan view thereof.

The broken lines that show the clip and other details on FIGS. 1-7 and the broken lines that define the bounds of the claimed design on FIGS. 1, 4, 5 and 7 are for illustrative purposes only and form no part of the claimed design.

The broken lines that define the bounds of the claimed design form no part thereof.
